WORK HOLDER

William B. Painter, Dearborn, Mich.

Application September 8, 1941, Serial No. 410,095

5 Claims. (Cl. 81—38)

This invention relates generally to work holders and refers more particularly to those designed for holding work upon a supporting surface of a vise.

Heretofore the devices for holding work upon a supporting surface of a vise have been objectionable either because they raised or lifted the work relative to the supporting surface instead of holding it down thereon when the devices were operated by the jaws of the vise, or they were too complicated or expensive for practical purposes in a shop or factory.

In the present instance, I have overcome the objections mentioned by the provision of a simple and inexpensive hold-down that will actually force the work down and hold it down upon the supporting surface of the vise when the hold-down is operated by the jaws of said vise.

In the accompanying drawing:

Figure 1 is a fragmentary elevation of a vise, 20 and showing hold-downs embodying my invention upon opposite sides of work upon the supporting surface of said vise;

Figure 2 is a top plan view of one of the hold-downs;

Figure 3 is a cross section taken on the line 3—3 of Figure 2;

Figure 4 is a view similar to Figure 1, but showing a slight modification;

Figure 5 is a view similar to Figure 3, but showing another modification.

Referring now to the drawing, A is the supporting surface for the work, and B and C, respectively, are the cooperating jaws of a vise of conventional construction.

D designates the work resting upon the supporting surface A, while E and F, respectively, are the devices embodying my invention for holding the work D down upon said supporting surface A.

As shown, the devices E and F are upon opposite sides of the work D on the supporting surface A between the jaws B and C of the vise and are similar in construction. Each device comprises an elongated member 10, preferably a metal bar, substantially wedge-shape in cross section, having inclined side edges 11 and 12, respectively, and a substantially flat bottom 13 provided substantially midway said edges with a longitudinally extending rib 14 of substantially rectangular cross section.

When placed on the supporting surface A, the inclined rear edges 11 of the bars extend downwardly and away from the jaws B and C of the vise, while the inclined front edges 12 extend upwardly and away from the work D. The rib 14

rests upon the supporting surface A of the vise and thereby spaces above said supporting surface the inclined edges 11 and 12, so that upon operation of one or both jaws B and C, the bars E and F will tip or rock on the ribs 14 in the direction of the arrows 15 and 16, respectively. In doing so, the forward edges 12 of the bars E and F will not only engage and bear firmly against the adjacent sides of the work D near the bottom thereof but will exert a positive and constant downward pressure upon the work so as to urge or force said work down and hold it firmly upon the supporting surface A of the vise.

In Figure 4 I have illustrated a slight modification wherein the hold-downs E' and F' are used on top of conventional uprights or parallels G and H, respectively, disposed between the work D' and the jaws B' and C' of a vise. As shown, the hold-downs E' and F' are identical in construction to the hold-downs E and F illustrated in Figures 1 to 3, inclusive, but are used on top of the parallels G and H, respectively, for engagement with the work D' near its upper end. When one or both jaws B' and C' are operated, the hold-downs E' and F' will tip or rock on the parallels G and H in the direction of the arrows 17 and 18, respectively, and in doing so will cause the forward edges 12' of the bars to initially engage and bear firmly against the adjacent sides of the work D' and then to urge the work down and hold it firmly upon the supporting surface A' of the vise.

In Figure 5, I have illustrated another modification wherein the rib 14^a on the underside of the bar E^a constituting the work holder extends transversely thereof from its inclined rear edge 11^a to a point in spaced relation to the inclined front edge 12^a. Thus, the forward edge 12^a of the bar will be spaced above and clear of the supporting surface such as A of a vise, but may swing or move downwardly relative thereto when forcing or holding the work down on the supporting surface of the vise.

In either instance, the bars constituting the hold-downs may be any length or width desired and may be formed of any suitable material. The essence of the invention resides in the provision of the ribs upon the underside thereof in combination with the inclined side edges respectively so that the forward edges of the hold-downs will initially be spaced above the supporting surface of the vise and such hold-downs may tip or rock as aforesaid to force the work down and hold it down on the supporting surface of the vise.

What I claim as my invention is:

1. A device of the class described for use with the clamping jaws of a vise for holding an interposed piece of work down upon the supporting surface of the vise, comprising an elongated member substantially wedge shape in cross section having a substantially flat bottom provided with a longitudinally extending supporting rib of substantially rectangular cross section for rocking engagement with said supporting surface, said 10 elongated member being entirely separate from the vise and adapted to extend transversely of the vise between one of the clamping jaws thereof and the work piece and having opposite longitudinal edges thereof inclined upwardly and rearwardly with respect to said work piece, the construction and arrangement of the rib and inclined edges of said member being such that the point of contact between the foremost inclined edge of the member and work piece is above the supporting surface of the vise but below the plane of contact between the rearmost inclined edge of said member and clamping jaw so that such member is adapted upon being actuated by one of 20 said clamping jaws to rock on the rib aforesaid and thereby exert a downward pressure against the work piece to hold the same firmly upon the supporting surface of the vise.

2. A one piece device of the class described for use with the clamping jaws of a vise for holding an interposed piece of work down upon the supporting surface of the vise, comprising an elongated member substantially wedge shape in cross section provided on the underside thereof with a longitudinally extending supporting rib for rocking engagement with said supporting surface, said elongated member being entirely separate from the vise and adapted to extend transversely thereof between one of the clamping jaws thereof and the work piece and having opposite longitudinal edges thereof inclined upwardly and rearwardly with respect to said work piece, the construction and arrangement of the rib and inclined edges of said member being such that the point of contact between the foremost inclined edge of the member and work piece is above the supporting surface of the vise but below the plane of contact between the rearmost inclined edge of said member and clamping jaw so that such member is adapted upon being actuated by one of 30 said clamping jaws to rock on the rib aforesaid and thereby exert a downward pressure against the work piece to hold the same firmly upon the supporting surface of the vise.

3. A device of the class described adapted to be inserted between a work piece and a clamping jaw of a vise for holding said work piece down upon the supporting surface of the vise, comprising an elongated member provided on the underside thereof substantially midway opposite longitudinal edges thereof with a longitudinally extending supporting rib for rocking engagement with said supporting surface, said elongated member being entirely separate from the vise and adapted to extend transversely thereof between 40 the clamping jaw thereof and the work piece, op-

posite longitudinal edges of said member being inclined upwardly and rearwardly with respect to said work piece, the construction and arrangement of the rib and inclined edges of said member being such that the point of contact between the foremost inclined edge of the member and work piece is above the supporting surface of the vise but below the plane of contact between the rearmost inclined edge of said member and clamping jaw so that such member is adapted upon being urged by said clamping jaw against said work piece to rock on the rib aforesaid and thereby exert a downward pressure against the work piece to hold the same firmly upon the supporting surface of the vise.

4. A device of the class described for use with the clamping jaws of a vise for holding an interposed piece of work down upon the supporting surface of the vise, comprising an elongated member entirely separate from the vise and adapted to extend transversely thereof between a clamping jaw thereof and the work piece and having opposite longitudinal edges thereof inclined upwardly and rearwardly with respect to the work piece, the underside of said member being provided transversely thereof from its rearmost inclined edge to a point in spaced relation to its foremost inclined edge with a longitudinally extending supporting rib for rocking engagement with the supporting surface of the vise, the point of contact between the foremost inclined edge and work piece being spaced by said rib above the supporting surface of the vise but being below the plane of contact between the rearmost inclined edge of said member and clamping jaw whereby said member is adapted upon being urged by said jaw against said work piece to rock on said rib and exert a downward pressure against the work piece to hold the same firmly upon the supporting surface therefor of the vise.

5. A one piece device of the class described for use with the clamping jaws of a vise for holding an interposed piece of work down upon the supporting surface of the vise, comprising an elongated member entirely separate from the vise and adapted to extend transversely thereof between a clamping jaw thereof and the work piece and having opposite longitudinal edges thereof inclined upwardly and rearwardly with respect to the work piece, the point of contact between the foremost inclined edge and work piece being below the plane of contact between the rearmost inclined edge of said member and clamping jaw whereby said member is operable upon being urged by said jaw against said work piece to exert a downward pressure against the work piece to hold the same firmly upon the supporting surface therefor of the vise, the underside of said member being provided with a longitudinally extending supporting rib for rocking engagement with said supporting surface, the construction and arrangement of said rib relative to said member being such that the point of contact between the foremost inclined edge of the member and the work piece is initially spaced above the supporting surface of the vise.
